CONVERSION OF DICYCLIC DIHYDROTERPENES TO CYCLOPENTENE HYDROCARBONS AND PENTAMETHYLENE HYDROCARBONS

Vladimir N. Ipatieff and Herman Pines, Riverside, Ill., assignors to Universal Oil Products Company, Chicago, Ill., a corporation of Delaware

No Drawing. Application July 29, 1943,
Serial No. 496,566

11 Claims. (Cl. 260—666)

The present invention relates to the catalytic conversion of hydrocarbons and more particularly to the treatment of dicyclic hydrocarbons to form monocyclic hydrocarbons having the same empirical formula.

We have discovered that by treating a dicyclic hydrocarbon of the terpene type with a dilute aqueous solution of a hydrolyzable salt or a dilute aqueous solution of a strong acid it is possible to prepare valuable hydrocarbon compounds which may be used as a motor fuel, solvents or raw materials for organic synthesis, perfume manufacture, etc.

One object of our invention is to provide a method for effecting the structural rearrangement of carbon atoms of dicyclic hydrocarbons having at least one strained ring.

A further object of our invention is to furnish a new method of isomerizing cyclic hydrocarbons containing at least one six-member ring into monocyclic hydrocarbons having a five-member ring.

Broadly, the present invention relates to the treatment of dicyclic hydrocarbons, having at least one strained ring, with a dilute aqueous solution of a hydrolyzable salt or a dilute aqueous solution of an acid to effect the isomerization of the dicyclic hydrocarbon to a compound having fewer carbon atoms in the ring.

According to Baeyer's strain theory, if the four bonds of a carbon atom are directed toward the vertices of a regular tetrahedron, each forms an angle of 109° 28' with the others. Any deviation from this angle is considered to cause a condition of strain which is accompanied by a corresponding decrease in stability. This angle size holds true for five and six-member rings but in forming smaller rings or larger rings the angle is much different. Under those conditions the bonds are under tension or are strained, and the compounds are relatively unstable.

In one embodiment, the present invention relates to a process which comprises preparing a monocyclic hydrocarbon having a five-member ring by contacting a dicyclic hydrocarbon containing a six-member ring with a catalyst comprising a dilute aqueous solution of an acid-acting salt.

A particular feature of our invention resides in the use of catalytic materials comprising dilute aqueous solutions of readily hydrolyzable salts such as the halides, phosphates, or sulphates of aluminum, zinc, cobalt, magnesium, iron, etc. If desired, the free acids can be used in place of the salts.

Hydrocarbons which may be employed in the process will include any dicyclic dihydroterpene having a ring of six carbon atoms and at least one strained ring of three or four carbon atoms. Examples of charging stocks are the dicyclic dihydroterpenes such as pinane, carane, thujane, sabinane, etc. The mechanism of the reaction is believed to involve the opening of one of the rings and isomerization of the six-member ring to a five-member ring. The product on hydrogenation yields saturated cyclic hydrocarbons which can be proved to be composed of pentamethylene rings.

The temperature at which the reaction takes place may be varied over a wide range depending upon the particular hydrocarbon charged and the catalyst employed, but will generally be within the range of about 150 to about 500° C. and preferably within the range of about 250 to 400° C.

Pressures employed in the process may vary between atmospheric up to about 500 atmospheres and are preferably from about 15 up to about 350 atmospheres. The catalyst concentration may range from about 0.25% up to about 50% and should preferably be from about 0.5% to about 15%. The amount of catalyst used will depend upon the temperature and type of hydrocarbon treated.

The operation may be carried out either as a batch or continuous process. The reaction mixture is kept under pressure so that the hydrocarbon layer may be easily drawn off. After separation from the aqueous solution the hydrocarbon layer is washed, dried, and distilled to separate the products.

The following example is introduced to illustrate the results obtainable in the practice of the present process in the conversion of pinane to alkylated cyclopentane, but is not intended to limit the scope of the invention in accordance with the data submitted.

Example

138 grams of pinane, 150 cc. of water, and 5 grams of magnesium chloride hexahydrate were placed in a steel rotating autoclave containing a glass liner. The reaction was conducted at a temperature of 350° C. and the maximum pressure developed at this temperature was 230 atmospheres. The product resulting from the reaction was separated from the aqueous solution, washed, dried, and submitted to a high temperature Podbielnik distillation. The product con-

sisted of hydrocarbons having the following boiling range:

Cut	Temp., °C.	Total, per cent by vol.	n_{D}^{20}
1-2	106-155	3.0	1.4441
3-4	155-157	7.6	1.4458-1.4467
5-8	157-158	22.8	1.4472 d_{4}^{20} 0.8003
9-12	158-160	34.9	1.4485-1.4498
13-20	160-162	54.0	1.4502-1.4538
21-24	162-164	65.1	1.4540-1.4551
25-28	164-165	81.9	1.4559-1.4570
29-31	165-167	87.8	1.4570-1.4571
32-34	167-169	95.4	1.4572-1.4594

Cuts 5 to 8 were hydrogenated, with an absorption of one mol of hydrogen per mol of product. The hydrogenated material had the following physical properties: boiling point 159-161°, n_{D}^{20} 1.4330,

d_{4}^{20} 0.7889

The hydrogenated product did not undergo dehydrogenation when passed over platinized alumina at 275° C., indicating the absence of hexamethylene hydrocarbons. The chemical behavior and physical constants show that the product before hydrogenation consists of alkylated cyclopentene. 80 per cent of cuts 25 to 28 were found to contain five-member rings. By recycling the hydrocarbon material an ultimate yield of over 90 per cent of cyclopentene hydrocarbons based on the pinane charged may be obtained.

We claim as our invention:

1. A process for producing alkyl cyclopentenes which comprises subjecting pinane to the action of an aqueous solution of magnesium chloride at a temperature of from about 150 to about 500° C. to isomerize the pinane into the alkyl cyclopentene.

2. A process for producing cyclopentene hydrocarbons which comprises isomerizing a dicyclic dihydroterpene containing a ring having six carbon atoms and a ring having at least three but not more than four carbon atoms by subjecting said dicyclic dihydroterpene under superatmospheric pressure and at a temperature of from about 150° C. to about 500° C. to the action of an acidic aqueous solution containing from about 0.25% to about 50% by weight of an acid-acting inorganic compound.

3. The process as defined in claim 2 further characterized in that said inorganic compound is a mineral acid.

4. The process as defined in claim 2 further characterized in that said inorganic compound is a salt of a mineral acid.

5. A process for producing cyclopentene hydrocarbons which comprises isomerizing a dicyclic dihydroterpene containing a ring having six carbon atoms and a ring having at least three

but not more than four carbon atoms by subjecting said dicyclic dihydroterpene under superatmospheric pressure and at a temperature of from about 250° C. to about 400° C. to the action of an aqueous solution of an acid-acting salt of a mineral acid.

6. The process as defined in claim 5 further characterized in that said salt is magnesium chloride.

7. A process for producing cyclopentene hydrocarbons which comprises subjecting a dicyclic dihydroterpene containing a ring having six carbon atoms and a ring having at least three but not more than four carbon atoms to the action of an aqueous solution of an acid-acting salt of a mineral acid at an isomerizing temperature of from about 150° C. to about 500° C.

8. The process as defined in claim 7 further characterized in that said salt is magnesium chloride.

9. A process for producing pentamethylene hydrocarbons which comprises isomerizing a dicyclic dihydroterpene containing a ring having six carbon atoms and a ring having at least three

but not more than four carbon atoms by subjecting said dicyclic dihydroterpene under superatmospheric pressure and at a temperature of from about 150° C. to about 500° C. to the action of an acidic aqueous solution containing from about 0.25% to about 50% by weight of an acid-acting inorganic compound, thereby forming alkyl cyclopentene hydrocarbons, and hydrogenating the latter to produce said pentamethylene hydrocarbons.

10. A process for producing pentamethylene hydrocarbons which comprises isomerizing a dicyclic dihydroterpene containing a ring having six carbon atoms and a ring having at least three but not more than four carbon atoms by subjecting said dicyclic dihydroterpene under superatmospheric pressure and at a temperature of from about 250° C. to about 400° C. to the action of an aqueous solution of an acid-acting salt of a mineral acid, thereby forming alkyl cyclopentene hydrocarbons, and hydrogenating the latter to produce said pentamethylene hydrocarbons.

11. A process for producing pentamethylene hydrocarbons which comprises subjecting a dicyclic dihydroterpene containing a ring having six carbon atoms and a ring having at least three but not more than four carbon atoms to the action of an aqueous solution of an acid-acting salt of a mineral acid at an isomerizing temperature of from about 150° C. to about 500° C., thereby forming alkyl cyclopentene hydrocarbons, and hydrogenating the latter to produce said pentamethylene hydrocarbons.
